FINN SIMMONS, OF NEW YORK, N. Y., ASSIGNOR, BY DIRECT AND MESNE ASSIGNMENTS, TO THE K & S FURNITURE COMPANY, INC., A CORPORATION OF NEW YORK.

FOLDING CHAIR.

1,188,499.

Specification of Letters Patent. Patented June 27, 1916.

Application filed September 11, 1913. Serial No. 789,277.

To all whom it may concern:

Be it known that I, FINN SIMMONS, a citizen of the United States, and a resident of New York, borough of Brooklyn, county 5 of Kings, and State of New York, have invented a certain new and useful Improvement in Folding Chairs, of which the following is a full, clear, and exact specification.

10 This invention relates more particularly to a class of foldable furniture.
My invention has for its object primarily 15 to provide a folding chair adapted for use at places when it is desired to arrange the chair into a compact parcel after being used so as to be portable or conveniently stored if desired as well as permitting a large number of the chairs to be readily transported in packages of comparatively limited 20 sizes, and wherein is employed a substantially U-shaped seat-frame composed of two side members having the corresponding ends thereof pivoted to the ends of a transverse member so that the side members may 25 be folded toward each other upon the transverse member.

Other objects of the invention are to provide a substantially U-shaped back having 30 three arms which are pivoted together so as to be folded in a similar manner to the seat-frame; to provide a substantially U-shaped supporting element having three bars pivoted together for being folded correspondingly to the seat-frame and which 35 serve as the front legs of the chair; to provide retaining plates for pivotally connecting the seat-frame, the back and said leg together; to provide a second substantially 40 U-shaped supporting element which is pivoted to the central part of the front legs and serves as the rear legs of the chair, these legs being composed of three bars pivoted together so as to be also folded together; and to provide two standards which 45 are pivoted to the side bars of the front leg and adjustably held to the seat-frame for supporting said seat-frame when the chair is unfolded for use.

A further object of the invention is to 50 provide a flexible covering for the seat-frame and back-frame of the chair, and which is adapted to be employed as a casing

for inclosing the chair when folded; and still a further object of the invention is to provide a folding chair which is susceptible 55 of being made so as to be light in weight, but which may combine great strength and durability.

With these and other objects in view, the invention will be hereinafter more particularly described with reference to the accompanying drawing, which forms a part of this specification, and will then be pointed out in the claims at the end of the description.

In the drawing, Figure 1 is a perspective view of one form of folding chair embodying my invention. Fig. 2 is a side view of the chair when the parts of the frame thereof are folded together. Fig. 3 is a view 70 looking downward upon the seat-frame of the chair with the flexible seat thereof directed outwardly, and Fig. 4 is a view of the folded frame of the chair showing the manner of wrapping the flexible seat there- 75 of around the parts to form a casing.

The folding chair has a substantially U-shaped seat-frame 10 composed of two side members, or bars 11 and 12, and to one of the corresponding ends of said side bars 80 is pivoted a transverse bar 13. The opposite end of each of the side bars 11 and 12 is pivotally held centrally between the spaced side walls 14 and 15 of each of two retaining plates, as 16 and 17, both of which are substantially U-shaped.

Adapted to be hingedly swung to an overlapping position upon the seat-frame 10 is a substantially U-shaped back-frame 18 having side arms 19 and 20, the lower ends 90 of which are pivoted between the upper parts of the side walls of the retaining plates 16 and 17, and to the opposite ends of said side arms are pivoted the ends of a transverse bar 21.

Hingedly movable to an overlapping position also upon the seat-frame 10 is a substantially U-shaped support 22 which serves as the front legs of the chair. The support 22 has side members 23 and 24, and to the 100 lower ends of said side members is pivoted a transverse third member, or rod 25. The free ends of the side members of the front legs, or support 22 are pivoted between the

lower parts of the side walls of the retaining plates 16 and 17 so that by pivoting the seat-frame, the back-frame, and the front legs in this manner to the retaining plates these parts may be moved together, and by pivotally connecting the members of each part the side members thereof may be folded upon the transverse members by directing the side members relatively toward each other in overlapping arrangement.

Pivots movable to rest against the underside of the front legs, or support 22 is a substantially U-shaped second support, as 26, which serves as the rear legs of the chair. The support, or rear legs 26 have side members 27 and 28, and the lower ends of said side members are pivoted to a transverse member, or rod 29. The upper end of the side member 27 is pivoted approximately centrally of the side member 23 of the front legs, and the upper end of the side member 28 is pivoted substantially centrally of the side member 24 of the front legs of the chair. The rear legs may thereby be swung so as to rest against the underside of the front legs 22, and the side members of the rear legs are also adapted to be relatively guided upon the transverse member thereof simultaneously with the folding of the frame-seat, the back-frame and the front legs of the chair, as above described.

Serving to hold the rear legs 26 in adjusted position, as shown in Fig. 1, when the chair is unfolded for use, I provide two foldable locking elements, as 30 and 31, both of which are similarly formed. Each of the locking elements is composed of two arms 32 and 33, and each pair of the arms have the opposite ends thereof pivoted together, at 34. The free ends of the arms 32 of the elements are pivoted to the central portion of the side members of the rear legs 26, and the free ends of the arms 33 of said elements are pivoted to the central parts of the side members of the front legs 22. To fold the locking elements 30 and 31 the pivoted portions of the arms thereof are forced in an upwardly direction, and the rear legs may then be swung to abut against the front legs. When unfolding the parts of the chair for use the rear legs are rearwardly disposed of the front legs, and when adjusted the pivoted parts of the arms of the locking elements are directed downwardly so that the arms of each locking element are on alinement. The rear legs will then be held against accidental movement.

For the purpose of maintaining the seat-frame 10 at a suitable height when the chair is unfolded, two hingedly adjustable standards, as 35 and 36, are provided. The lower ends of the standards 35 and 36 are pivoted to the front portions of the side members of the front legs 22, and upon the upper ends of the standards are provided sleeves,

as 37 and 38. One of the sleeves 37 and 38 is slidably movable upon each of the side members of the seat-frame 10 so that by adjusting the sleeves upon the seat-frame the standards 35 and 36 will also be positioned for elevating, or lowering the seat-frame to a suitable height. In folding the chair the sleeves 37 and 38 as well as the standards 35 and 36 are guided in directions toward the retaining plates 16 and 17, and the front legs may then be moved against the seat-frame to permit the chair to be folded.

In order to hold the parts of the chair in their normal positions when unfolded for use, and to prevent all tendency of the parts to collapse inwardly, or move outwardly by the weight of the person using the chair, to the retaining plate 16 is pivotally held one end of a transverse rod 39 having a hook 40 upon its other end. Upon the retaining plate 17 is provided an eye 41 which is in the path of movement of the hook 40 of the rod 39 for reception of the hook when the chair is unfolded. On folding the chair the rod 39 is moved to free its hook with the eye 41, and the rod is then swung inwardly between the seat-frame 10 so as to rest against one of its side members to permit the parts of the chair to be folded together.

Upon the top of the seat-frame 10 and upon the back-frame 18 of the chair is an adjustable covering 42 adapted to serve as a casing for the chair when folded as well as serving as the seat and back proper of the chair. The covering 42 is approximately rectangular in shape, and may be of canvas, or other suitable flexible material. One end of the covering 42 is fixedly attached to the transverse bar 21 of the back-frame 18, and the opposite end of said covering is secured to the transverse bar 13 of the seat-frame 10. The side edges of the covering will thereby be normally free of connection with the seat-frame and the back-frame. In order to detachably secure the side edges of the covering to the seat-frame and to the back-frame when the chair is unfolded, at spaced intervals upon each side edge of the covering are a number of hooks, as 43, and at spaced intervals transversely of the central part of the covering are also a number of corresponding hooks 44. When the parts of the chair are relatively arranged in unfolded positions the hooks 43 are disposed over the side members of the seat-frame 10 and over the side members of the back-frame 18, and the hooks 44 are guided over the rod 39. To fold the chair the hooks 43 and 44 are released from engagement with the seat-frame, with the back-frame, and with the rod 39. The covering is then directed outwardly from between the seat-frame and the back-frame. After the hook

40 of the rod 39 is removed from the eye 41 the rod is swung inwardly between the seat-frame, and the parts of the chair may be folded together as hereinbefore mentioned so as to be wrapped in the covering 42 which will then serve as a casing after the free part thereof is detachably secured to the body of the covering by any suitable means which may be provided upon said 10 covering.

In the foregoing description, I have embodied the preferred form of my invention, but I do not wish to be understood as limiting myself thereto, as I am aware that 15 modifications may be made therein without departing from the principle, or sacrificing any of the advantages of this invention, therefore I reserve to myself the right to make such changes as fairly fall within the 20 scope of the appended claims.

Having thus described my invention, I claim as new and desire to secure by Letters Patent:—

1. A folding chair of the character described, comprising two spaced retaining plates, a substantially U-shaped seat-frame having the free ends thereof pivoted to the retaining plates, a substantially U-shaped back-frame having the free ends thereof pivoted to the retaining plates so as to be 25 swung upon the seat-frame, substantially U-shaped front legs having the free ends thereof pivoted to the retaining plates so as to be also swung upon the seat-frame, the back-frame, the seat-frame, and the front legs having their side members pivoted to the transverse members whereby the side members of each may be simultaneously moved to overlapping positions upon the 30 transverse members thereof when the seat-frame, the back-frame, and the front legs are in abutting arrangement, substantially U-shaped rear legs having the free ends thereof pivoted to the front legs so as to be 35 swung upon the front legs, the side members of said rear legs being pivoted to the transverse member thereof so as to be folded correspondingly to the folding of the front legs, the seat-frame, and the back-frame, a 40 locking element removably held between the retaining plates to prevent the side members of the seat-frame, the back-frame and the front legs from collapsing or moving outwardly when the chair is unfolded, a substantially rectangular flexible seat having 45 one of its ends secured to the transverse member of the back-frame, and having its other end secured to the transverse member of the seat-frame, and means provided upon 50 the seat and serving to detachably fasten the sides of the seat to the side members of the seat-frame and to the side members of the back-frame.

2. A folding chair of the character described, comprising two spaced retaining

plates substantially U-shaped, a substantially U-shaped seat-frame having the free ends thereof pivoted to the retaining plates, a substantially U-shaped back-frame having the free ends thereof pivoted to the retaining plates so as to be swung upon the seat-frame, substantially U-shaped front legs having the free ends thereof pivoted to the retaining plates so as to be swung upon the seat-frame, substantially U-shaped back legs 70 having their free ends pivoted to the front legs so as to be swung upon the front legs, the seat-frame, the back-frame, the front legs and the back legs each respectively, having their side members pivoted to their 80 respective transverse members whereby the side members may be simultaneously moved to overlapping positions upon the transverse members thereof when the seat-frame, the back-frame, the front legs and the back legs 85 are in abutting positions, a rod having one of its ends pivotally secured to one of the retaining plates and its other end adapted to be removably secured to the other retaining plate whereby the side members are 90 held from collapsing or spreading apart when the chair is in use, hinged folding members provided upon the side members of the front legs and the back legs to prevent the front legs and back legs from 95 spreading when the chair is in use, hinged standards provided upon the front legs and slidably connected to the side members of the seat-frame to support the seat-frame when the chair is in use, and a flexible seat, 100 substantially as shown and described.

3. In a folding chair of the character described, having two retaining members substantially U-shaped, a U-shaped seat-frame having its free ends pivoted in the retaining members, a U-shaped back-frame having its free ends pivoted in the retaining members so as to be swung upon the seat-frame, a U-shaped support adapted to serve as front legs, having its free ends pivoted in the 105 retaining plates so as to be swung upon the seat-frame, a U-shaped support adapted to serve as back legs having its free ends pivoted to the side members of the front legs so as to be swung upon the front-legs; the combination therewith of a plurality of corresponding pairs of elbow-joints adapted for pivotally connecting the side members of the U-shaped seat, the U-shaped back, the U-shaped front legs and the U-shaped back 110 legs to the respective transverse members thereof, whereby the side members may be moved into overlapping relation when the seat-frame, the back-frame, and front legs and back legs are in folded arrangement, 115 one of each of said pairs of elbow joints having an extended arm for connecting with the side member on one side of each of the U-shaped frames and the U-shaped supports, whereby said pivotal joint on one 120

4
side of the frame is at a greater distance from the transverse member of each respective frame and support than the pivotal joint on the other side of the said frame, whereby the side members may be disposed in overlapping relation parallel with the transverse member when the seat-frame, back-frame, front legs and back legs are

disposed in folded relation, substantially as shown and described. 10

This specification signed and witnessed this tenth day of September, A. D. 1913.

FINN SIMMONS.
